(Cl. D34—15)

To all whom it may concern:

Be it known that we, Hugo B. Meyer and William E. Lawson, Sr., citizens of the United States of America, and residents of Summit, in the county of Union and State of New Jersey, and Rahway, in the county of Union and State of New Jersey, respectively, have invented a new, original, and ornamental Design for an Inflatable Toy Horse, of which the following is a specification, reference being had to the accompanying drawings, forming a part hereof.

Fig. 1 is a side elevational view of a toy horse, showing our new design;

Fig. 2 is a plan view of the toy horse; and
Fig. 3 is a front view of the toy horse.

We claim:

The ornamental design for an inflatable toy horse, as shown.

HUGO B. MEYER.
